UNITED STATES PATENT OFFICE.

ULRICH KORNSTEIN, OF CHICAGO, ILLINOIS.

HAIR-DRYING COMB.

1,248,674.

Specification of Letters Patent.

Patented Dec. 4, 1917.

Application filed October 21, 1916. Serial No. 126,852.

To all whom it may concern:

Be it known that I, ULRICH KORNSTEIN, a citizen of the United States, residing at Chicago, in the county of Cook and State of Illinois, have invented a certain new and useful Improvement in Hair-Drying Combs, of which the following is a specification.

My invention relates to an improved construction of hair drying combs by which the 10 comb is formed from sheet metal in a manner to use as thin metal as possible in the back of the comb without sacrificing strength in the teeth, since the latter are formed by folding the sheet of metal upon itself as will 15 more fully appear below. My invention also consists in rigidly securing the handle of the comb to the hollow back thereof and providing the heating core or rod with a separate handle, so that both parts of the device may 20 be manipulated without burning the hands and in further providing a spring catch for holding the heating core in place in the hollow back. By my invention I further provide that the hair being dried may come 25 directly in contact with a portion of the hollow back of the comb by cutting teeth the full depth of the projecting sheet of folded metal extending from the hollow back, as a result of which the heat of the 30 core is communicated directly to the hair through the hollow back with a minimum loss by radiation.

Several drawings illustrating my invention are as follows:

35 Figure 1 shows the comb in side view with the heating core partially inserted therein, and

40 Fig. 2 is a transverse sectional view through the comb shown in Fig. 1, taken along the line 2—2.

Similar numerals refer to similar parts throughout the several views.

As shown in the drawings the comb consists of a thin sheet of metal, preferably of 45 aluminum, or other metal having good heat conducting properties, which is formed along one edge into a tube 10, the other edge being bent outwardly radially of the tube to form the teeth 11, and the outwardly extending portion being folded back 50 at the points of the teeth upon itself so as to make the teeth 11 of double thickness, as indicated more clearly in Fig. 2, the edge of the folded portion of the teeth preferably 55 extending as indicated in Fig. 2 to the inside of the bore of the tube 10. The teeth

11 are formed by cutting slots through the outwardly extending double portion, which slots extend preferably to the outer surface of the tube 10 as a result of which the 60 hair 12, being dried by the use of the comb, occupies a position somewhat as shown in Fig. 2 directly against the outer surface of the tube 10. A handle 13 is rigidly secured to the tube 10 by riveting or otherwise, so 65 that the comb may be conveniently operated and said handle is preferably of wood or other non-conductor of heat, so that the hand of the operator will not be burned in using the comb.

A heating rod or core 14 is provided of slightly smaller diameter than the bore of the tube 10 which rod has rigidly secured to one end a handle 15 of wood or other non-conducting material, so that the heating rod 70 may be handled without danger of burning the hand of the operator. The handle 15 has rigidly secured thereto a spring 16, the extending end of which is perforated at 75 17 to engage a pin or equivalent projection 18 80 from the outer surface of the open end of the tube 10 as a result of which the rod 14 is securely held in place in the tube 10 during the use of the comb.

The comb is used by first removing the 85 rod 14 from the tube 10 by lifting the end of the spring 16 after which the rod 14 is heated and then inserted in the tube 10. The heat of the rod is communicated to the tube 10 and thereby to the teeth 11, and 90 since the teeth are twice as thick as the tube 10 and good conducting path is afforded to the hair being dried, and furthermore, the hair coming directly in contact with a considerable portion of the outer surface of 95 the tube 10, a large part of the heat is communicated directly through the wall of the tube 10 with a minimum amount of heat lost to said hair in contact with said tube.

I do not limit myself to the exact detail 100 of construction shown and described above, as I may employ equivalents thereof known to the art at the time of the filing of this application.

I claim:

1. In a hair drying comb, the combination 110 of a sheet of conducting metal formed into a tube and having teeth of double thickness extending therefrom, a non-conducting handle rigidly secured to said tube, a metal heating rod, and a non-conducting handle rigidly secured to said heating rod, said

teeth being cut substantially to the outer surface of said tube and the folded portion of the sheet forming the teeth extending into the wall of the tube.

- 5 2. A hair drying comb comprising a sheet of metal formed into a tube and having projecting teeth formed from said sheet by folding the sheet of metal upon itself at the outer ends of said teeth, whereby the
- 10 teeth are of double the thickness of said tube and the folded portion of the sheet forming the teeth extends to the inside of the tube.

3. A hair drying comb comprising a sheet

of metal formed into a tube and having projecting teeth formed from said sheet by folding the sheet of metal upon itself at the outer ends of said teeth, whereby the teeth are of double the thickness of said tube, said teeth extending inwardly to the outer surface of said tube, and the folded sheet extending to the inner surface of the tube whereby the inner ends of said teeth are connected together.

In witness whereof, I hereunto subscribe my name this 10th day of October, A. D. 1916.

ULRICH KORNSTEIN.
